UNITED STATES PATENT OFFICE.

SAMUEL LIEBERKNECHT, OF HELLAM, PENNSYLVANIA.

DESIGN FOR A FEED-HOPPER.

43,427.

Specification for Design.

Patented Jan. 7, 1913.

Application filed October 28, 1912. Serial No. 728,296. Term of patent 14 years.

To all whom it may concern:

Be it known that I, SAMUEL LIEBERKNECHT, a citizen of the United States, residing at Hellam, in the county of York and State of Pennsylvania, have invented a new, original, and ornamental Design for Feed-Hoppers, of which the following is a specification, reference being had to the accompanying drawing, forming a part thereof.

Figure 1 is a perspective view of a feed

hopper showing my new design; Fig. 2 is a top plan view; Fig. 3 is a rear elevation.

I claim:

The ornamental design for a feed hopper, as shown.

SAMUEL LIEBERKNECHT.

Witnesses:

J. D. YOAKLEY,
FERDINAND ESPEY.
